UNITED STATES PATENT OFFICE.

JOHN D. PUGH, OF MOUNT WASHINGTON, BALTIMORE, MARYLAND.

METHOD OF AND APPARATUS FOR TRANSPORTING SLAG.

Application filed April 28, 1920. Serial No. 377,211.

To all whom it may concern:

Be it known that I, JOHN D. PUGH, a citizen of the United States, and residing at Mount Washington, Baltimore, Maryland, ⁵ have invented certain new and useful Improvements in Methods of and Apparatus for Transporting Slag, of which the following is a specification.

The object of this invention is to provide ¹⁰ a ladle for transporting molten slag produced by blast furnaces and similar industrial plants to remote points for its disposal, having novel and improved means whereby the slag is prevented from solidifying in the ¹⁵ ladle in cases where a considerable length of time elapses before the dumping point is reached.

In general, slag is a poor conductor of heat and it often happens that the outer ²⁰ layer of the liquid slag in a slag conveyor or ladle solidifies while the ladle is being transported due to the fact that the central portion of the slag will not transfer its heat to the outside layer as quickly as the outside ²⁵ layer will radiate its heat, the result being that the outer layer becomes chilled and solidifies while the inner portion is still very hot and in liquid condition. The invention contemplates the use, with a slag ³⁰ conveying ladle, of means for agitating the slag so that it circulates within the ladle and has no stationary outer layers which by rapid radiation will become chilled and solidified.

³⁵ The invention further contemplates means for introducing combustible material into the ladle, the materials so introduced being burned therein to keep the slag in a molten condition. This feature is of great practical value where slag is to be transported a considerable distance and where the ladle conveying the same may be delayed in transit, as for instance where the ladle is mounted upon a car body and is moved, with ⁴⁰ others, in a train to the dumping point.

In the drawings:

Figure 1 illustrates in side elevation a car having a slag conveying ladle mounted thereon which has two forms of the slag ⁴⁵ agitating and heating mechanism attached

thereto, portions of the ladle being broken away;

Figure 2 is a section on the line 2—2 of Figure 1;

Figure 3 is a section on the line 3—3 of ⁵⁵ Figure 1;

Figure 4 is a section on the line 4—4 of Figure 1;

Figure 5 is a view similar to Figure 1 but showing a modified form of heating and ⁶⁰ agitating apparatus.

The slag ladle L comprises a cylindrical central portion and conical end portions integral therewith, and its pivotally mounted at its ends on a specially designed car ⁶⁵ truck. This form of ladle, which is described and claimed in Patent No. 1,251,282, issued to me December 25, 1917, is well adapted to have the improved slag agitating and heating mechanism attached thereto, but ⁷⁰ it will be understood that other forms of ladles may be used if desired, and that the invention is not limited in its scope to the particular form of ladle illustrated and described. ⁷⁵

Preferably the ladle has an outer metallic casing 10 and an inner layer 11 of refractory material, capable of withstanding great heat. Spouts having covers 13 are provided on the cylindrical portion of the ladle above ⁸⁰ its central axis and equidistant horizontally therefrom, and the openings through these spouts constitute inlet and outlet openings for the molten slag.

In one form of the invention, illustrated ⁸⁵ in Figures 1 and 2, one of the conical end portions is provided with an opening 14 through which the inclined pipe 15 extends downwardly into the interior of the ladle. This pipe has an inner portion 16 of metal, and an outer coating of refractory material ⁹⁰ 17 and at its lower end is located a nozzle 18 of refractory material, bolted to the pipe 16 as is clearly illustrated in Figure 3, and having a central orifice 19. The upper end ⁹⁵ of the pipe 15 may be horizontal and has rigidly mounted thereon a fuel container or receptacle 20 having a hopper-shaped bottom and a removable cover 21.

This hopper 20 is adapted to contain pul- ¹⁰⁰

verulent fuel, such as coal or coke braize which passes through a restricted orifice in its bottom and into the interior of the horizontal portion of pipe 15. Located within the tube 15 are two compressed air nozzles, 22 and 23 respectively, which are connected to a pipe 24 leading to a source of compressed air, preferably an air compressor mounted upon the engine of the train of which the car comprises a unit. A valve 25 controls the passage of compressed air to the nozzles 22 and 23, and a second valve 26 is provided for the purpose of reducing the pressure of the air passing to the nozzle 23, if desired.

The collar 27 secured to the ladle has an aperture in alignment with the aperture 14 and this collar is provided with a set screw 28 which bears against a block 29 in contact with the pipe 15. By loosening the set screw the pipe 15 may be so adjusted that its outlet orifice 19 is at any desired depth below the surface of the molten slag contained in the ladle. A branch pipe 40 conducts air under pressure from the pipe 24 to the fuel reservoir 20 above the level of the fuel therein to insure a proper feeding of the fuel to the aspirating nozzles against the pressure in the pipe 15 resulting from the pressure of the slag at the mouth of the tube. A valve 41 enables the air pressure on the surface of the fuel to be regulated as desired.

In the operation of the device the compressed air which issues from the nozzles 22 and 23 conveys the pulverulent fuel downwardly into the body of molten slag where it is burned, the heat generated by its combustion being absorbed by the slag and the products of combustion passing upwardly and out through one of the spouts, the cover of which may be removed for that purpose. The quantity of air supplied by the nozzles 22 and 23 is sufficient to support the combustion of the fuel introduced, and its pressure is such that it will displace the slag tending to obstruct its flow. If desired, one of the nozzles 22 or 23 may be discarded and a single nozzle used. The compressed air and products of combustion passing upwardly through the molten slag agitate the same, and cause currents of hot slag to flow from the center of the ladle toward and along the walls thereof preventing chilling and solidification of the outer layer of the material. This effect will be realized if air alone is introduced and, in some cases, the supplying of combustibles may be dispensed with.

Upon the other conical end portion of the ladle may be placed a second hopper 50, also adapted to contain pulverulent or granular fuel and to feed the same into a horizontal conduit 51 opening into the interior

of the ladle above the level of the slag. An aspirating nozzle 52 blows the fuel through this conduit and into the ladle where it is burned and serves to keep the slag in a molten condition. A pipe 53 provided with a regulating valve 54 conducts air under pressure to the hopper above the surface of the fuel therein to insure a proper feeding of the fuel to the aspirating nozzle. It will be apparent however that in this construction the back pressure will be negligible as the orifice of the conduit 51 is above the level of the slag, and the air pipe 53 may be dispensed with, if desired.

In the form of the invention illustrated in Figure 5 the fuel tank 20' is suitable for oil or other liquid fuel, which passes downwardly through conduit 30 into pipe 15', where it is atomized by an air nozzle 22', connected to a suitable source of compressed air. The pipe 15' is provided with two branch pipes 31 and 32 of flexible material and armored to resist the destructive effect of molten slag in case slag should enter the same. The pipe 31 has an orifice 33 in the top of the ladle and pipe 32 has an orifice 34 in the bottom of the ladle. Suitable valves 35, 36 and 37, control the passage of fuel and air from the atomizer through the pipes 15', 31 and 32 respectively, so that any of these may be cut off or all may be used, as desired. The pipe 15' is adjustable, as in the first form described, the connected flexible pipes 31 and 32 having sufficient looseness to permit any desired adjustment.

A pipe 40' provided with a regulating valve 41' conducts air under pressure to the fuel tank above the fuel level to insure proper feeding of the fuel to the pipe 15' against the pressure existing therein due to the pressure of the slag at the mouth of the tube.

By this arrangement a flame may be burned above the surface of the slag, or at the bottom of the slag ladle, or at any depth beneath the surface of the slag found desirable.

While it is desirable to use a ladle of the type illustrated and described in connection with the slag heating and agitating means, it will be understood that other types of ladles may be employed if desired. Furthermore, while only oil and pulverulent materials are mentioned as fuel, natural or manufactured gases may be employed whenever they may be obtained cheaply, these gases being preferably stored under compression in tanks and supplied in proper amounts through a conduit controlled by a reducing valve. Still other kinds of fuel may be used if found suitable. By providing the fuel containers with an ample supply of fuel, the slag may be transported long distances or may be maintained within the

- ladle in a completely molten state for long periods of time, advantages not realized by the various slag ladles heretofore designed or suggested.
- 5 Having thus described the invention what is claimed as new and desired to be secured by Letters Patent is:
1. In a device for transporting molten material, in combination, a ladle, and means including a pipe adjustably mounted on said ladle and having an orifice within the same for introducing combustible material into the slag at any desired depth below its surface, for the purpose set forth. 65
  - 10 2. In a device for transporting molten material, in combination, a ladle having an aperture, and means for introducing a combustible material into the slag at any desired depth below its surface, including a pipe 70 extending through said aperture and having an outlet orifice within said ladle, and means on said ladle for adjustably securing said pipe in position. 75
  - 15 3. In a device for transporting molten material, in combination, a ladle and means including a fuel hopper mounted on the ladle and a compressed air handling device associated therewith, for introducing pulverulent material into said ladle, for the 80 purpose set forth. 85
  - 20 4. In a device for transporting molten material, in combination, a ladle and means including a hopper mounted on the ladle and opening into a conduit which communicates with the ladle, and a compressed air nozzle in said conduit, for introducing pulverulent material into said ladle, for the 90 purpose set forth. 95
  - 25 5. In a wheeled device for transporting molten material, in combination, a ladle and means for introducing combustible material into the material through the bottom of the ladle, for the purpose set forth. 100
  - 30 6. In a wheeled car for transporting molten material, in combination, a tiltable ladle mounted on the car frame and means including a fuel supply tank supported on the ladle, for introducing combustible material 105 into the ladle, for the purpose set forth. 110
  - 35 7. In a wheeled car for transporting molten material, in combination, a ladle formed to completely enclose a material retaining chamber, an opening being provided in the top for the introduction and withdrawal of molten material, and means being provided 115 for the introduction of combustible material into the chamber to heat the material, the products of combustion escaping from the chamber through said opening. 120
  - 40 8. In a wheeled car for transporting material, in combination, a ladle having heavy walls of heat resistant material, the walls completely enclosing a material retaining chamber having a relatively small opening 125
  - 45 in its top for the introduction and withdrawal of material in a molten condition, and means on said car for introducing combustible material into the chamber to be burned to heat the slag, the products of combustion escaping through said opening. 70
  - 50 9. In a wheeled car for transporting molten material, in combination, a ladle, and means for introducing a combustible material into said ladle below the surface of the material including a pipe having its outlet orifice inside the ladle and below the level of the surface of the material, a fuel tank opening into said pipe above the level of the surface of the slag, and means for conducting compressed air to said tank and pipe. 80
  - 55 10. In a wheeled car for transporting molten material, in combination, a ladle, and means for introducing a combustible material into said ladle below the surface of the material including a pipe having its outlet orifice inside the ladle and below the level of the surface of the material, a fuel tank opening into said pipe above the level of the surface of the material, and means for conducting compressed air into the fuel tank to force fuel into the pipe and means for conducting compressed air into the upper end of the pipe to entrain the fuel issuing from the fuel tank and force it through the pipe and into the body of the material. 95
  - 60 11. The method of maintaining material in a liquid state while being transported in a ladle consisting in introducing a combustible mixture into the body of the material which ignites therein, the products of combustion flowing upwardly therethrough to agitate and heat the slag. 100
  - 65 12. A car for transporting materials in a molten state including in combination, a wheeled support, a container for such material substantially closed and designed to retain heat, said container having a restricted opening in its top, and means for introducing a gas into the body of the material in said container. 105
  - 70 13. A car for transporting materials in a molten state including in combination, a wheeled support, a container for such material substantially closed and designed to retain heat, said container having a restricted opening in its top, a fuel reservoir, and means for introducing fuel from said reservoir into said container. 115
  - 75 14. A container for transporting molten materials having a substantially closed body and designed to retain heat, said container having openings in the bottom and top for the introduction of combustible material and escape of the products of combustion respectively, and means on the container for introducing combustible material through said bottom opening. 120
  - 80
  - 85
  - 90
  - 95
  - 100
  - 105
  - 110
  - 115
  - 120
  - 125

15. In a device for transporting molten material, in combination, a ladle and means including a fuel supply reservoir mounted on the ladle and a fuel conduit associated therewith, for introducing a combustible fuel into the body of the material.

16. In a device for transporting molten material, in combination, a ladle and means

including a fuel supply reservoir mounted on the ladle, a fuel conduit associated therewith, and means for supplying compressed air to the fuel conduit, the fuel conduit having its outlet for fuel and compressed air within the body of the material.

In testimony whereof I affix my signature.

JOHN D. PUGH.
